UNITED STATES PATENT OFFICE.

CLARENCE A. TRULL, OF WACO, TEXAS.

PUZZLE.

1,206,034.

Specification of Letters Patent. Patented Nov. 28, 1916.

Application filed February 26, 1916. Serial No. 80,693.

To all whom it may concern:

Be it known that I, CLARENCE A. TRULL, a citizen of the United States, residing at Waco, in the county of McLennan and State 5 of Texas, have invented certain new and useful Improvements in Puzzles, of which the following is a specification, reference being had to the accompanying drawings.

This invention relates to an improved 10 puzzle and has for its primary object to provide a very simple device which is highly amusing and requires considerable patience and skill in its solving.

It is another and more particular object 15 of the invention to provide a puzzle consisting primarily in the provision of a suitable base having a plurality of channels or grooves cut in its surface extending in various angular directions and differently colored with respect to each other, and a plurality of movable members corresponding to each of the colored channels and movable therein, whereby, by proper manipulation, the members of one color may be assembled in a groove or channel of the same 25 color.

With the above and other objects in view, my invention consists in the novel features of construction, combination and arrangement of parts to be hereinafter more fully 30 described, claimed and illustrated in the accompanying drawing, in which,

Figure 1 is a plan view of my puzzle; and Fig. 2 is a transverse section taken on the 35 line 2—2 of Fig. 1.

Referring in detail to the drawing, 5 designates the base section of a substantially rectangular body. This base section has a plurality of channels or grooves indicated at 6, 7 and 8 respectively, cut in its upper surface. These channels have concave base walls, and these walls are differently colored, preferably red, white and blue respectively.

45 A pair of balls 9 are provided for each groove and are colored correspondingly thereto. These balls may roll freely in the grooves and are permanently held therein by means of a top section 10 of the base 50 which is relatively thin and is fixed or secured in any suitable manner upon the surface of the body section 5. It is to be observed that the balls are of substantially the same diameter as the grooves in the base 55 section 5 so that one ball cannot pass another in said grooves. The top section 10

is also provided with slots, indicated at 11, 12 and 13 respectively, which have a common communicating point in like manner to the channels 6, 7 and 8, and coincide with 60 the latter channels. The balls 9 project to a sufficient distance above the upper surface of the base section 10 through the slots therein to enable the fingers to be readily engaged with said balls. 65

It will be observed from reference to Fig. 1, that the slots and channels define the letter Y, and each arm of the Y is sufficiently long to contain three of the balls 9. In the operation of the device, assuming that balls of the same color are arranged in a groove of a different color as shown in Fig. 1, the would-be solver is required to place the colored balls in grooves of corresponding colors. In order to do this, it is 70 manifest that considerable manipulation of the balls in the grooves is necessary and considerable patience is required before the balls will be arranged in the desired manner. The operation may be reversed and 75 the balls of the same color assembled in a groove of a different color which is quite as difficult as the operation first referred to. It is thus seen that, in an exceedingly simple device, I have produced a very interesting and amusing puzzle. 80

While I have above referred to a preferred form of the body for the puzzle, it will be understood that the same may be of any preferred shape in plan, and the 90 length of the grooves and the number of balls increased if desired. The device is also susceptible of other obvious modifications and it will, therefore, be understood that I reserve the privilege of adopting all 95 such legitimate changes as may be fairly embodied within the spirit and scope of the invention as claimed.

Having thus fully described my invention, what I desire to claim and secure by 100 Letters Patent is:—

1. A puzzle consisting of a base having a plurality of grooves in its surface extending in different angular directions and having a common communicating point, the walls of each groove being colored differently from the walls of the remaining grooves, and a plurality of movable elements for each groove corresponding in color thereto. 105

2. A puzzle consisting of a base having a plurality of grooves in its surface communi- 110

cating at the same point, a plurality of elements for each groove movable therein, the several grooves and certain of the elements having a common characteristic whereby the 5 same may be distinguished from the remaining elements and every other groove.

3. A puzzle consisting of a base having a plurality of grooves in its surface extending in different angular directions and having 10 a common communicating point, the walls of each groove being differently colored from the walls of the other grooves, and a plurality of balls corresponding in color to the respective grooves and of such 15 diameter as to be movable in the grooves.

4. A puzzle consisting of a base having a plurality of grooves in its surface extending in different angular directions and having 20 a common communicating point, the walls of each groove being differently colored from the walls of the other grooves, a plurality of balls of substantially the same diameter as the respective grooves and colored correspondingly thereto, and means for

retaining the balls in the grooves but permitting of their free rolling movement 25 therein.

5. A puzzle consisting of a base having a plurality of grooves in its surface extending in different angular directions and having 30 a common communicating point, the walls of each groove being differently colored from the walls of the remaining grooves, a plurality of balls for each groove colored correspondingly thereto, each groove being 35 of such length as to contain one ball in addition to the number of balls which are of the same color as said groove, and means secured upon the base to retain the balls in the grooves but permit of their free rolling 40 movement therein.

In testimony whereof I hereunto affix my signature in the presence of two witnesses.

CLARENCE A. TRULL.
